DESIGN FOR A GAME BOARD

Ralph J. Byrnes, Chicago, Ill.

Application March 11, 1935, Serial No. 55,807

Term of patent 14 years

To all whom it may concern:

Be it known that I, Ralph J. Byrnes, residing at Chicago, in the county of Cook and State of Illinois, a citizen of the United States, have invented a new, original, and ornamental Design for a Game Board, of which the following is a specification, reference being had to the accompanying drawing, forming a part thereof.

The figure is a top plan view of a game board showing my new design. The third dimension of the board is plain and may be of any desired thickness.

I claim:

The ornamental design for a game board substantially as shown and described.

RALPH J. BYRNES.
